Primary Examiner — Richard E Chilcot(57) **CLAIM**

The ornamental design for a phone cover, as shown and described.

DESCRIPTION

FIG. 1 is a perspective view of a phone cover showing my new design, shown in a closed position;

FIG. 2 is a perspective view of the phone cover shown in a first open position;

FIG. 3 is a front elevational view of the phone cover shown in FIG. 1;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front elevational view of the phone cover shown in a second open position; and,

FIG. 10 is a front elevational view of the phone cover shown in a third open position.

The broken lines in the drawings depict stitching that form parts of the claimed design.

1 Claim, 10 Drawing Sheets(56)
